FIG 4

W. C. Nein Inventor

by
Thomas Howe

Attorney

UNITED STATES PATENT OFFICE.

WILLIAM C. NEIN, OF NEW YORK, N. Y.

REVERSE-CURRENT CONTROLLER.

Application filed March 15, 1920. Serial No. 365,803.

To all whom it may concern:

Be it known that I, WILLIAM C. NEIN, a citizen of the United States of America, residing at city of New York, county of Bronx, and State of New York, have invented new and useful Improvements in Reverse-Current Controllers, of which the following is a specification.

This invention relates to means for permitting current from a source of electrical energy to pass through the windings of an electrical device in a predetermined direction only. It is particularly useful for preventing demagnetization of the permanent magnets of a magneto or similar device resulting from current connections of wrong polarity but may have other uses.

The main object of the invention is to provide apparatus of the character indicated.

Another object of the invention is to provide apparatus of the character described whereby, when used with magnetos as referred to, the permanent magnets of the magneto or similar device are employed in effecting desired control.

Another object of the invention is to provide apparatus of the character described whereby a relay is employed either externally to or internally of a magneto or similar device or a switch to accomplish the desired result.

Other and ancillary objects of the invention will appear hereinafter.

In the accompanying drawings which illustrate the invention;

Fig. 1 is a diagram illustrating apparatus and connections embodying the invention as applied to a magneto, the magneto structure including modifications for effecting the invention;

Fig. 2 is a diagram showing apparatus and connections embodying the invention as applied to a magneto, the structure of the magneto itself being unmodified from the usual practice and the invention being accomplished by suitably constructed and connected accessories;

Fig. 3 is a diagram showing an embodiment of the invention wherein the current controlling relay is constructed as an adjunct to what is generally known as an auxiliary vibrating coil used in connection with a magneto;

Fig. 4 is a diagram showing an arrangement similar to Fig. 2 but with a different wiring arrangement.

Referring to the drawings and first to Fig. 1, which shows in diagram the electrical connections and circuits also the magnetic circuits of the invention as applied to what is commonly known as a battery starting type magneto, 1 and 2 are the permanent magnets, 3 a magnetic core, 4 a magnetic rotor, and 5 a magnetic end piece, these parts forming the magnetic circuit of an inductor type magneto 6 and 7 are respectively the high and low tension windings of the magneto, 8 and 9 are respectively the movable and stationary parts of the usual circuit breaker which is operated by the cam 10 on the magneto shaft 11 and 12 are pieces of soft iron fastened to magnetic end pieces 3 and 5 respectively by means of the screws 13 and 14, and terminating in cores 15 and 16 which are wound with coils 17 and 18 respectively. 19 is a thin strip of spring steel biased by its spring away from the cores and secured to the soft iron piece 11 by means of screws 21 and 22 but insulated therefrom by the block 20. 23 and 24 are insulated terminals of the magneto to which the usual connections are made from the operating switch 25, the switch 25 being a three way switch having the positions "magneto," "off" and "battery" which as well as other details of construction not mentioned heretofore are familiar to one skilled in the art. One of the stationary contacts for the "battery" (lefthand) position of the switch is connected to the battery or other suitable source of electrical energy at 26, the battery having one terminal grounded at 27 and the other connected to one point of the switch which is grounded as illustrated. The other stationary contact is connected with the terminal 23.

In the "off" (middle) position of the switch, one of the stationary contacts is connected to the ground at 28 and the other stationary contact is connected with the magneto terminal 24 while in the "magneto" (right hand) position the stationary contacts are unconnected.

As stated above the main object of the invention is to provide apparatus which will allow an electric current from a source of

electrical energy to pass through the windings of an electrical device in a predetermined direction only. The application of the invention as illustrated in Fig. 1 is to provide protection for the permanent magnets of a magneto against demagnetization due to current connections of the wrong polarity. Thus the iron pieces 11 and 12 with the intervening air gap between their cores 15 and 16 are in magnetic shunt to the branch containing the magneto pole piece and rotor so that the spring 19 is normally attracted against its bias by magnetism from the permanent magnets and establishes a ground connection for the primary coil 7 of the magneto. If the current from the battery is passing in the proper direction, that is in such direction that the magneto motive force of the coils 17 and 18 will oppose that of the permanent magnet, the spring 19 will be released and move against the contact 34 thereby establishing a connection of the end of the coil 7 with the terminal 23. If the battery current is not in the right direction, the magneto motive force of the coils 17 and 18 will reinforce that of the cores 15 and 16 due to the permanent magnet and the spring 19 will remain in attracted position. The right direction of battery current is that in which its effect in flowing through the coil 7 is to reinforce the magneto motive force of the permanent magnets so that it does not tend to deenergize those magnets.

In order to clearly set forth the operation of the apparatus the path of the current may be followed through the several circuits from one terminal of the battery to the other: Assuming the operating switch in "battery" position, circuit may be traced from one terminal of the battery 26 along conductor 29, switch 25, conductor 30 to insulated terminal 23, along conductor 31 through electromagnets 17 and 18 and in such direction as to oppose the magnetization by the permanent magnet.

The electromagnets 17 and 18 are so proportioned that when energized the biased steel spring 19 which is normally held down is released and assumes the position 33 making contact 34 and allowing current to pass through it along conductor 35 and through coil 7 (in such a direction as to have a magnetizing effect on magnets 1 and 2), insulated terminal 24, conductor 26, movable part 8 of the circuit breaker, stationary part 9 of circuit breaker and conductor 37 to ground 38 and thence back to the negative terminal of the battery 26 by ground 27 and conductor 39.

The foregoing is the action resulting from connecting the correct terminal or pole of the battery 26 to the magneto at terminal 23. If, however, the incorrect pole is connected, current in passing through electromagnets 17 and 18 sets up such polarities as

to assist in holding the biased steel spring 19 firmer than before against contact 40 and which therefore does not permit the current to pass through the coil 7 of the magneto and which current in this case would be of such polarity as to oppose the permanent magnets 1 and 2 and which in practice would be of sufficient strength to demagnetize them.

With the switch 25 in the "off" position, the battery will be out of circuit so that the spring 19 will be held against the contact 40 which is connected with ground. Also the switch 25 will connect the terminal 24 with the ground at 28 so that the coil 7 is short circuited through the two grounds just referred to. In the "magneto" position of the operating switch the connections will be the same as in the "off" position except that the ground 28 will be disconnected from the terminal 24 which will be connected with the ground 38 through the conductors 36 and 37 and the interrupter.

It will be seen that the circuit of the battery, when the operating switch is in "battery" position, will be made through the coils 17 and 18 regardless of whether the battery circuit is completed through the winding 7 or not. It is thus made unnecessary that the energizing current for the coils 17 and 18 should pass through the winding 7 so that the latter receives no current unless it is in the proper direction.

Referring to Fig. 2 the magneto, as in Fig. 1, comprises the core 3' on which are wound the secondary coil 6' and the primary coil 7', the latter being connected with the magneto terminals 23' and 24'. The terminal 24' is connected through the conductor 36' and the interrupter 8'-9' operated by the cam 10', on the magneto shaft, the contact 9' being connected through the conductor 37' with the ground at 38'.

Also an operating switch 25' similar to the operating switch of Fig. 1 is provided which has its contacts connected in the same way with the ground at 28' and with the conductor 29' extending to one terminal of the battery 26' which has its other terminal connected by the terminal 39' with the ground at 27'.

Independent of the magnetic structure is provided an automatic switching device for preventing the battery current from passing in the wrong direction. This switching device comprises a suitably supported permanent magnet 41 to one end of which is secured the core 43 by a screw 44. Mounted upon an insulating block 46 which is secured to the magnet 41 by means of a screw 48, is a steel spring 45 mounted upon the insulating block 46 and secured thereto by means of a screw 47. The spring is normally biased to occupy the position as indicated by dotted lines at 51 but when attracted by

the magnetism of the magnet 41 it will be drawn into the position shown in full lines, thus occupying positions in contact with the contacts 53 and 49 in its respective positions.

5 Wound upon the core 43 is a coil 42 which is in circuit with the battery when the operating switch 25' is in battery position and is wound so that when the battery current is flowing in the proper direction the magneto motive force of 42 will oppose the magnetism of the permanent magnet and will release the spring 45 so that it will come against the contact 53.

10 The circuits and operation of the apparatus may be traced as follows:

Starting from the positive terminal of the battery the path of the current extends along the conductor 29, the battery terminals of the switch 25, conductor 30', conductor 31' and coil 42 to ground. If the current is in the right direction so that the current of the coil 42 opposes the magnetism from the magnet 41, the steel spring will be released and come against the contact 53 whereupon circuit will be made from the conductor 30' through the contact 53, spring 45, conductor 54, magneto terminal 23', magneto primary coil 7', terminal 34', conductor 36', interrupter 8'-9' and conductor 37' to ground 38'. If, however, the battery current is not flowing in the proper direction it will be the reverse of that as previously supposed so that the coil 42 will reinforce the permanent magnet and the spring 45 will be the more firmly attracted so that the circuit of the magneto through the battery will be interrupted at the contact 53.

Referring now to Fig. 3, the magneto, as in the preceding figures, comprises a core 3" on which are wound the secondary coil 6" and the primary coil 7". One terminal of the coil 7" is connected with ground, the other with the magneto terminal 24" which is connected through a conductor 36" and an interrupter comprising the movable and fixed contacts 8" and 9", the former being operated by a cam 10" and the latter being connected by a conductor 32" with the ground at 28". Also there is provided an operating switch 25" similar to the analogous switches in the preceding figures, one of the points of the "off" position being connected with a ground at 28" and the other point of that position being connected by a conductor 68 with the magneto terminal 24". One of the battery points of the switch is connected through a conductor 29" with one terminal of the battery 26", the other terminal of the battery being connected through 60 the terminal 28" with the ground at 27". One of the points of switch 25" is connected with the junction 66. From the junction 66 one circuit extends to a terminal of the coil 65 of the vibrator usual in the ignition cir-

cuit. The other terminal of the coil 65 is 65 connected with a steel spring 61 normally biased by its spring so as to be in engagement with the contact 64. When, however, the spring 61 is attracted by the magnet having the coil 65, the spring will be moved 70 out of contact with the contact 64 thereby breaking the circuit at that point. From the contact 64 a conductor 67 extends to the device for preventing current passing in the wrong direction. The conductor 67 is connected to the steel spring 51" which is biased so as to normally stand away from the core 43" and in contact with the contact 53". The core 43" is mounted on the permanent magnet 41" so as to be energized 80 thereby to attract the spring 51", this latter spring being insulated by being mounted upon an insulating block 46" it being secured thereto by means of a screw 47", and core 43" and the block 46" are secured to 85 the permanent magnet by means of screws 44" and 48" respectively.

Upon the core 43" is a coil 42" one end of which is connected with the junction 66 and the other end being connected through 90 the conductor 52" with the ground at 50". The direction of the winding 42" is such that when current passes in the proper direction from the battery to the magneto, the magneto motive force of coil 42" will be 95 such to oppose that of the permanent magnet 41".

When the direction of current is right therefore the magnetizing action of the permanent magnet will be neutralized by that of the coil 42" to such an extent that the steel spring 51" will be released and spring back against the contact 53". If, however, the current should be going in the other and wrong direction, the magneto motive force of the coil 42" will reinforce that of the permanent magnet and the spring 51" will be securely attracted away from the contact 53" so that the circuit is broken at that point. With the operating switch in 110 battery position circuits may be placed as follows:

From the positive terminal of the battery along conductor 29", through switch 25", to junction 66, where it divides, one part being through coil 42" and conductor 52" to ground at 50", the polarities of coil 42" opposing the permanent magnet 41" which in turn releases spring 45" which assumes the position 51" coming in contact with 115 the contact 53". Starting again at junction 66 the other path is through the winding 65 of the vibrating coil 60, through the vibrating spring 61, contact 64, conductor 67, spring 61, contact 53", conductor 68 and magneto terminal 24" whence the circuit passes through the winding to ground thereby completing the circuit through the bat- 120 125

tery and the coil 7", it having been observed that a terminal of the battery also is connected to ground.

Circuit is made as above when the positive terminal of the battery is connected to switch 25. In case the negative terminal is so connected, the circuit in passing through the coil 42" would cause polarity such that it would assist the permanent magnet 41" to hold the spring 45" more firmly than before, thus preventing it from making contact with the contact 53". The circuit will thus be opened at this contact and current will be prevented from passing through the coil 7", in this, the wrong direction.

Referring to Fig. 4 there is shown therein an arrangement requiring only one conductor leading to the magneto, the arrangement being otherwise similar to that shown in Fig. 2. In Fig. 4 there is a magneto as in the previous apparatus comprising a core 3^a upon which are wound coils 6^a and 7^a which are the secondary and primary windings respectively. The primary winding has its terminal connected with the magneto terminals 23^a and 24^a. The latter terminal is connected through the conductor 36^a with the interrupter 8^a—9^a which is operated by a cam 10^a on the magneto shaft, and whereby connection is made and broken through the conductor 37^a with the ground at 38^a. Also there is the operating switch 25^a which is similar to the previously described switches of this character but differs therefrom somewhat in its connections as will appear hereinafter.

One of the points of this switch in the magneto position is connected to the ground at 28^a and the other point is connected with the magneto terminal 23^a and also with the switch contact 53^a. The points in the "off" position are not connected while those in the battery position are connected, one, through the conductor 29^a and the battery 26^a with the ground at 27^a, while the other point of that switch position is connected to the spring 51^a and also with one terminal of the coil 42^a upon the core 43^a which is mounted upon the permanent magnet 41^a. The other terminal of the coil 42^a is connected through the conductor 52^a with ground at 50^a.

With the switch in the battery position, circuit may be traced from the positive terminal of the battery 26^a through the conductor 29^a to the operating switch, thence the circuit passes into two branches, one to one terminal of the winding 42^a and thence to ground as before referred to, and the other to the steel spring 51^a which, as before explained, tends to stand away from the core 42^a and against the contact 53^a. With the positive terminal of the battery connected as described, current in

the coil 42^a will oppose the magnetism set up by the permanent magnet so that the steel spring 45^a will be released and come against the contact 53^a, thence circuit may be traced through the magneto terminal 23^a and thence through the coil 7^a to ground. If, however, the battery should have its connections reversed, current would pass in the reverse direction through the coil 42^a so that the magneto motive force of that coil will reinforce that of the permanent magnet and more securely hold the spring 45^a away from the contact 53^a, the permanent magnet tending to hold the spring 45^a in this position and actually so doing so when the coil 42^a is deenergized.

With the spring 45^a thus held away from the contact 53^a the circuit through the battery and coil 7 will be broken. Thus it is that if current tends to be passed through the coil 7 in the wrong direction the apparatus described will prevent it.

While the invention has been illustrated in what are considered its best applications, it may have other embodiments without departing from its spirit and is not therefore limited to the structures shown in the drawings.

What I claim is:

1. The combination with a magneto having a permanent magnet of primary and secondary windings receiving the magnetism from said magnet, switching mechanism controlling the circuit through said source and said primary winding, said switching mechanism tending to maintain circuit closed through said primary winding and source, a permanent magnet acting on said switching mechanism to open the circuit of said primary winding and an electromagnet receiving current from said source and opposing the magneto motive force of said permanent magnet so as to permit the closing of the circuit through said source and primary winding when the current tends to flow in the proper direction through said primary winding.

2. In an ignition system, the combination of an ignition current generator having permanent field magnets, an auxiliary source of current adapted to supply unidirectional current, manual means for connecting the generating winding of the generator to said auxiliary source of current, and automatic means for preventing all flow of current from the auxiliary source through the generating winding except when said current flows in a predetermined direction.

3. In an ignition system, the combination of an ignition current generator having permanent magnets, an auxiliary source of current adapted to supply unidirectional current, manual means for connecting the generating winding of the generator to said auxiliary source of current, and automatic

means controlled by current from the said auxiliary source for preventing all flow of current from said source through the generating winding other than in a predetermined direction.

4. In an ignition system, the combination of an ignition current generator having permanent field magnets, an auxiliary source of current adapted to supply unidirectional current, manual means for connecting the generating winding of the generator to said auxiliary source of current, and automatic switch devices comprising electro-magnetic actuating means adapted to close the circuit between the auxiliary source and the generating winding when the current from said source flows in a predetermined direction in relation to the winding and to maintain said circuit open when the current from the source is not flowing or is flowing in the opposite direction.

5. In an ignition system, the combination with an ignition current generator having permanent field magnets, a generating winding inductively arranged in the field of said magnets, and a rotor adapted by its movement to vary the flux passing through the generating winding without reversing the direction of the flux in relation to said winding, of an auxiliary source of current adapted to supply unidirectional current, manual means for connecting the generating winding of the generator to said source of current, and automatic means for preventing all flow of current from the auxiliary source through the generating winding other than in a predetermined direction adapted to exert a magnetizing influence on the permanent magnets of the generator.

In testimony whereof I have signed this 12th day of March, 1920.

WILLIAM C. NEIN.
